UNITED STATES PATENT OFFICE.

LERoy G. BERIGAN, OF MADISON, WISCONSIN, ASSIGNOR TO FRENCH BATTERY COMPANY, OF MADISON, WISCONSIN, A CORPORATION OF WISCONSIN.

DRY CELL AND METHOD OF MANUFACTURE.

Application filed February 5, 1925. Serial No. 7,046.

This invention relates particularly to the core or "bobbin" of a dry cell, which forms the positive electrode in the cell.

The primary object is to provide a core with a wrapper applied in an improved manner.

It is common practice to form such a core by molding a mixture of carbonaceous material, such as carbon flour and graphite, a suitable depolarizing material, and suitable salts, such as zinc chloride and ammonium chloride, a carbon pencil being imbedded in the body, preferably during the molding operation.

Such a core, or body, is quite fragile. Hitherto, it has been the most usual practice to wrap the core in cheese cloth and secure the wrapping on the core by means of wrappings of thread. Many efforts have been made to evolve practices suitable for factory operations which omit the cheese cloth wrapping or provide some substitute for the securing of the wrapper on the core by winding a string or thread about the core and tying the string or thread. Many of the methods which have been proposed involve the use of coatings which are applied either to the surface of the depolarizing body, or core, or to the wrapping which envelopes the core. There are objections to the use of such coatings, in practice. One series objection is that the use of the coating tends to inhibit or interfere with the free electrolytic action which should occur when the cell is in use.

During periods when the cost of cheese cloth is not excessive, there are reasons, in factory practice, why it is desirable to use such a wrapping, provided the labor expense can be kept low enough and provided the operation of applying the wrapper can be so facilitated as to insure a maximum output of product.

The present invention utilizes an exceedingly simple and effective method of applying a bibulous cover, or wrapping, to a core of the character mentioned; and the wrapping, when applied in accordance with the improved method, will not interfere with the free chemical action which is desired in the cell. According to the improved method, the wrapper, which preferably comprises a strip of cheese cloth, has its upper and lower margins dipped in melted paraffin, or in other suitable adhesive. The core is then rolled

into the wrapper, leaving the ends of the wrapper projecting in the form of tubular extensions. These tubular extensions then are tucked in in folds over the ends of the core, and adhere together so as to adequately secure the wrapper on the core.

The invention is illustrated in its preferred embodiment in the accompanying drawing, in which—

Fig. 1 represents a core embodying the invention, from which a portion of the wrapping has been opened; Fig. 2, an elevational view of the completed core; Fig. 3, a top plan view of the same; Fig. 4, a bottom plan view of the same; and Fig. 5, a sectional view of a cell in accordance with the invention.

In the illustration given, A represents a core for a dry cell molded from a mixture comprising a suitable carbonaceous material and equipped with a carbon pencil A'; and B represents a wrapper which preferably is a strip of cheese cloth, but which may be a strip of paper. The strip of cheese cloth, or other bibulous wrapper, preferably is of such length as to wrap upon the core and have the vertical margins overlap slightly. The upper and lower margins are designated 1 and 2. These margins preferably are dipped in melted paraffin. The space between the upper and lower margins is of a width corresponding approximately with the height of the body A. The upper and lower dipped, or coated, margins 1 and 2 are of suitable width to enable them to be folded over and tucked down on the end surfaces of the body A.

The preferred method of applying the wrapper, where the operation is performed by hand, is to roll the core in the wrapper until the wrapper completely envelops the cylindrical surface of the core and the vertical margins of the wrapper overlap, thus leaving the paraffined margins projecting in the form of cylindrical extensions. These extensions are then bent over in folds and pressed against the end surfaces of the core. Thus, in Fig. 3, the upper margin 1 has been tucked down upon the upper surface of the body A to form the tucks, or folds, 1^a; and in Fig. 4, the lower margin 2 has been tucked in and pressed against the lower surface of the body A in the form of tucks, or folds, 2^a. These folds overlap and adhere to each other and adhere also to the end surfaces of the core. The paraffin may cool, of

course, before the wrapper is applied to the core, but it is found, in practice, that when the paraffined margins are pressed upon each other and against the end surfaces of the core, the tucks will adhere together and to the core in such a manner as to provide a very secure envelope for the core.

In Fig. 2, the vertical margins 3 and 4 of the wrapper are shown as overlapping. In practice, the overlap may be very slight, or may even be omitted.

After the core has been formed in the manner described, it is introduced into a zinc can 5, and the cell is provided with an electrolyte 6 which sets in the form of a paste. The electrolyte may be introduced either before or after the insertion of the core. In the illustration given, the cell is completed by introducing a pasteboard washer 7 above the core and pouring in melted pitch, or wax, to form a seal 8.

It has been the practice, hitherto, where a cheese cloth wrapping has been applied to the core and secured by wrappings of twine, or thread, to then dip the lower end of the wrapped core in paraffin. Another expedient is to place a paraffined disk in the bottom of the zinc can, for insulation. In accordance with the improved process, the paraffined tucks at the bottom of the core afford a sufficient insulation between the bottom of the core and the bottom of the can.

The wrappers may be applied to the cores very expeditiously by hand, if desired. However, the improved method lends itself readily to machine operation in effecting the wrapping of the core. Any suitable machine, or apparatus may be employed for effecting the wrapping and tucking operations. Thus, the cost of applying to a core a wrapper which will not interfere with the action of the cell may be reduced to a minimum, and a hitherto tedious method of applying wrappers is eliminated. The improved process, obviously, is an important item in the manufacture of dry cells of this type, where the manufacture in some factories may run into the hundred thousands per day.

A further advantage of the improved method of wrapping is that the wrapper is applied very smoothly to the core, and thus a cell may be completed without danger of trapping air in the electrolyte in the annular space between the core and the can. Hence, there is a uniform distribution of electrolyte between the core and the can. As is known in the use of the cell, as well as in the manufacture of the cell, the cheese cloth serves to prevent the migration of particles of carbon, or graphite, into the electrolyte, and thus tends to prevent injury to, or destruction of, the cell.

65 The paraffin employed to coat, or satu-

rate, the upper and lower margins of the cheese cloth is an insulating adhesive which is of rather a waxy nature. This material gives to the wrapper, at the coated portions, a certain degree of stiffness, so that the tucks of the wrapper when pressed against the ends of the core assume a set, or fixed, condition. This adhesive is not readily affected by the electrolyte in its fluid condition, or before it has become gelatinized; hence, the core may be introduced into a cup containing the fluid electrolyte in sufficient quantity to fill, or approximately fill, the annular space, and this may be done without danger of disintegrating the adhesive or causing a loosening of the tucks. Any suitable adhesive which will serve this purpose may be employed as an equivalent of the paraffin which it is preferred to embody, and this is to be understood in construing the annexed claims.

The foregoing detailed description has been given for clearness of understanding only, and no unnecessary limitations should be understood therefrom, but the appended claims should be construed as broadly as permissible, in view of the prior art.

What I regard as new, and desire to secure by Letters Patent, is:

1. A dry cell comprising a zinc cup, a core therein comprising carbonaceous material, a wrapper of thin fabric on said core having upper and lower margins provided with resistant adhesive insulating coatings and formed into tucks pressed against the upper and lower surfaces of the core, said tucks being secured in position by said adhesive coating, the portion of the wrapper enveloping the circumferential surface of the core being unimpregnated with the adhesive, and an electrolyte between the wrapped core and the zinc cup.

2. For use in a dry cell, a wrapped core comprising a depolarizing body and a bibulous wrapper enveloping said body, said wrapper having its lower margin impregnated with an adhesive of insulating character, said margin being pressed in folds against the lower surface of the core and said folds being secured in place by said adhesive and the portion of the wrapper enveloping the cylindrical surface of the core being left unimpregnated.

3. A wrapped core for use in dry cells comprising a body of depolarizing mix and a wrapper enveloping said body comprising a strip of cheese cloth having upper and lower margins impregnated with paraffin and pressed in folds against the upper and lower ends of the core, the portion of the wrapper about said cylindrical core being unimpregnated and said folds being secured in position by the paraffin.

4. A wrapped core for use in dry cells

- comprising a molded cylindrical body of suitable depolarizing mix, and a thin wrapper enveloping said core comprising a strip of cheese cloth wrapped on the core and 20
6 having overlapping vertical margins, said wrapper having upper and lower margins impregnated with a wax-like adhesive, said upper and lower margins being folded in tucks pressed against and adhering to the 25
10 upper and lower surfaces of the core, the portion of the wrapper enveloping the circumferential surface of the core being unimpregnated with the adhesive.
5. The method of wrapping a core for a 30
15 dry cell which comprises: impregnating the upper and lower margins only of a thin, non-resilient strip of bibulous material with an adhesive, wrapping the strip about the core, and tucking the impregnated margins against the end surfaces of the core and securing the tucks in position by said adhesive.
6. The method of applying an envelope to a core for use in a dry cell which comprises: impregnating the upper and lower margins of a strip of cheese cloth, wrapping the strip about the core with the impregnated margins projecting in an annular form, and tucking the annular projecting margins against the upper and lower surfaces of the core and securing the tucks in position by means of said adhesive.
